LABEL-APPLYING MECHANISM.

Original application filed January 27, 1921, Serial No. 440,378. Divided and this application filed
February 16, 1923. Serial No. 619,418.

This invention relates to mechanism for applying labels to articles or packages. The mechanism is especially constructed and adapted for use in a machine for applying an outer wrapper around a package, the ends of this wrapper being folded inward to form end flaps, and these flaps being sealed by the cementing against them of labels. The label-applying mechanism of the present invention may be otherwise useful or available.

The present application is a division of our application for patent for package wrapping machines, filed January 27, 1921, Serial No. 440,378.

In the machine described and shown in that application, previously formed packages (containing coffee or other material) are fed into the machine and covered with a wrapper (of waxed or glassine paper) drawn from a roll from which a sufficient length for one wrapper is cut off. This wrapper being held momentarily on a table, a package is fed over it and forced downward by a plunger descending from above, which pushes it down into a pocket located just beneath such table, during which movement the wrapper is folded around three sides of the package, leaving upstanding flaps which are then folded down over the top of the package and folded together, whereby the wrapper forms an open-ended tube enclosing the package and projecting beyond the ends thereof. The pocket, which is one of a series carried by an endless chain moving intermittently, is then advanced to another position or station where the package is exactly centered in the wrapper, and then successively to other stations, at one of which the ends of the wrapper are folded in against the ends of the package by the action of a succession of folders, after which folding operations heated irons advance against the opposite ends and hold the folds from unfolding while softening the wax or other preparation in the paper to render the folded end flaps limp, so that they will not spring open. The pocket is then advanced to the next station, fixed guides engaging the end flaps and holding them from unfolding during this movement. Labels or seals are then applied to the opposite ends being that of Fig. 3 (this view corresponds of the package to seal down the end flaps. 105

This is best accomplished by first causing pads to which a thin coating of paste or glue has been applied, to press against the ends of the package; as these recede, plungers advance and press gummed labels or seals against the end flaps, so that each label adheres to the end flaps and holds them closed together. Each label-affixing device comprises a label-holding cartridge or magazine which is carried by a plunger and contains a stack of labels pressed forward by an internal spring, the end label being pulled out at each movement by its adhesion to the end of the package. The next advance movement of the pocket carries the ends of the package between plates which extend along the path of travel, whereby the labels are kept pressed against the end flaps until dry. Finally, the pocket carrying the wrapped package comes opposite an ejecting plunger which slides the package endwise out of the pocket onto a conveyer belt which carries it away.

For a complete illustration and description of the machine thus briefly indicated, reference is made to the application above referred to.

In the accompanying drawings so much of the machine above described is shown as will enable the part of the mechanism to which the present application is directed, to be understood.

Figure 1 is a sectional side elevation of the machine corresponding to Fig. 1 of said application, but omitting those parts not necessary to the understanding of the structure herein claimed.

Fig. 2 is a plan view showing partly in section so much of the mechanism indicated at the right-hand side of Fig. 1 as concerns the present invention. (This view corresponds to part of Fig. 2 of said application, and partly to Fig. 16 thereof).

Fig. 3 is a vertical transverse section taken generally on the line 3-3 in Figs. 1 and 2. Fig. 4 is a fragmentary vertical transverse section on a larger scale, in the plane of the line 4-4 in Fig. 2. (This corresponding to Fig. 17 of said application).

Fig. 5 is a similar transverse section showing the parts in another position, the plane of the package to seal down the end flaps. 105

Fig. 6 is a plan and horizontal section of the label magazine (the view corresponding to Fig. 19 of said application).

Fig. 7 is a detail of the plates for holding 5 the end flaps folded (corresponding to Fig. 43 of said application).

Fig. 8 is a perspective view of the completed package with its label attached (being similar to Fig. 42 of said application).

10 In describing the drawings we will use the same numbers and letters of reference as in said prior application.

The packages to be wrapped are fed into the machine in any suitable manner and 15 brought to the position of the package a in Fig. 1 over a pair of wings or trap doors $e e$ which form a temporary support. The wrapping paper f is drawn from a roll f' following the path indicated in Fig. 1, being 20 cut off by shears B into wrappers, the severed wrapper resting momentarily on a table A .

A series of pockets or receptacles $C C$ are connected by an endless chain D or other 25 suitable intermittently-moving carrier, and are guided by guides E . Each pocket has a movable false bottom C' . In the initial position a pocket stands directly beneath the package a in Fig. 1, with its false bottom 30 elevated. The table A has at its middle a gap or opening directly beneath the package. A plunger m above the package descends and forces it down, causing the trap doors $e e$ to swing downwardly; the package 35 is pushed down through the gap in the table, carrying the wrapper with it, and is entered fully into the pocket, the false bottom C' yielding to this movement. This operation folds the wrapper around three 40 sides of the package, leaving two flaps of the wrapper projecting upwardly. Immediately these are folded down over the top of the package and their edges folded together. Thus the wrapper is formed into 45 a tube enclosing the package with its open ends projecting beyond the ends of the package. The chain D then moves forward so as to bring the package to the position a^2 ; in this position the package is centered 50 within the tubular wrapper. At the next movement the package is brought to the position a^3 ; in this station the projecting ends of the wrapper are folded inward to form end flaps lying against the ends of the package. This folding is accomplished by 55 folder blades acting successively. As the last blade acts to complete the end folding, the heated iron or plate is moved against each end of the wrapper package, which 60 keeps the folded end flaps from unfolding, and softens the flaps and renders them limp to prevent their springing out. At the next movement of the chain the package is brought to the position a^4 . In moving to 65 this position the ends of the package are

received between plates 316 which bear against the edge of the package and prevent any possible turning out of the end flaps. It is in this position a^4 that the end labels are applied.

These end labels v are of such size that they overlie the top and bottom end flaps of the waxed paper wrapper and thereby seal these flaps and prevent the unfolding of the wrapper. They are applied simultaneously to opposite ends by mechanism best shown in Figs. 3 to 6. As the mechanisms are duplicated at opposite ends, those for one end alone need be described. First the end flaps of the wrapped package are moistened with a suitable adhesive (or it may be with water alone if the labels are already gummed) by means of a swinging pad M carried on an arm projecting from an oscillating shaft M' , and which in its upper position, shown in Figs. 3 and 4, receives adhesive from a traveling roller N and then swings down to press against the end flaps and apply the adhesive thereto, as shown in 70 Fig. 5. Immediately after the pad M swings up out of the way, a magazine P carrying the labels (which may be gummed or not) is moved forward, that is, toward and against the end of the wrapped package, being carried by a reciprocating slide 80 Q . The magazine P is pressed yieldingly against the end of the package while the mass or stack of labels within it is pressed forward, so that the end label is caused to 85 attach itself to the end flaps of the wrapper 90 by reason of the adhesive (either that applied by the pad M or that with which the label was previously coated, or both); whereupon the magazine P is carried back 95 away from the package far enough to be 100 out of the way of the next movement of the pad M .

The magazine P is yieldingly mounted in a carrier Q' carried on the slide Q , the magazine backing through a cushion spring w against a head Q^2 which is pressed forward by springs $R R$ (Fig. 6): As the magazine P strikes the end of the package it stops, while the parts Q and Q' continue to advance, the springs $R R$ taking up this 110 extra movement and holding the magazine against the package. The labels are pressed forward by a follower P' within the magazine, which is swivelled on the end of a screw P^2 which turns little by little in the head Q^2 to advance the follower enough to 115 compensate for the shortening of the stack of labels as these are fed off.

The label is so firmly pressed against the end of the package that it adheres thereto, and upon the withdrawal of the magazine on the back stroke of the slide, the edge of the label frees itself from the slightly in-turned end of the magazine and remains attached to the package.

Both the slide and the follower begin to move back before the magazine begins to retreat, the magazine being held against the package a fraction of a second longer by 5 the expansion of the spring w . This action permits the follower to move back sufficiently to relieve the label stack of any pressure which otherwise would tend to bind the labels against the restricted delivery end of 10 the magazine and prevent the ready withdrawal of the end label.

The package is advanced by the next movement of the pocket to the next stopping position, and at each succeeding movement 15 of the endless chain carrying the series of pockets it is advanced, so that it moves step by step to the ejecting position indicated at a^8 in Fig. 1. Between the positions a^4 and a^8 the end flaps and labels are dried, being 20 held against any possible separation by plates forming continuations of the plates 316. When each package reaches the ejecting position it is pushed out by means of an ejecting plunger (not shown), the successive packages being pushed along a trough U in which they travel end to end, as shown in Fig. 2.

The driving parts of the machine comprise a driving shaft 22, and driven shafts 30 26, 32, 34, and 49, these shafts being suitably geared together and driven in unison, and carrying suitable cams for applying movement to the operative parts of the machine. These motion-applying elements are 35 not here illustrated in detail, reference being made to said prior application for an understanding thereof. It is necessary here to describe only the means for operating the parts shown in Figs. 3 to 6.

40 The application of gum, water or other liquid to the ends of the packages preliminary to applying the end labels thereto, is accomplished by mechanism best shown in Figs. 2-6. On each side of the path of the pockets is a vessel 320 containing thin glue, paste or other adhesive, or even water. In 45 these two vessels turn cylinders 321 mounted on a transverse shaft 322 which may be driven at any desired speed by a belt on one of the pulleys 323 (Fig. 3). The transferring rollers N , already described, are mounted each on a bracket projecting from a reciprocating slide 324 moving longitudinally of the machine between the positions shown 50 in full and dotted lines in Fig. 2. The slides 324 are reciprocated by mechanism driven from a cam 325 (Fig. 1) on the shaft 34, the cam roller being carried by a lever 326, its free lower end connecting by a link 328 with 55 an arm 329 (Fig. 2) of the lever 330, the outer end of the arm of which connects by a link 331 to one of the slides 324; the lever 329, 330, has also an arm 332 which engages through a pin and slot coupling with a similar arm on another lever 330' (Fig. 2) which

communicates like movement through another link 331' to the other of the slides 324, so that these two slides move together and to like extent. When the roller N is in contact with the cylinder 321, as seen in Fig. 2, 70 it is desirable that it should be revolved otherwise than by such contact, and to this end its shaft carries on the opposite end a friction roller 333 which in such position bears against a friction drive wheel 334 75 fixed on the shaft 322. As the rollers N are carried away from 321 they pass under the pads M and thereby transfer the glue or other liquid thereto.

The applying pads M are mounted on 80 crank arms on rock shafts M' , whereby they swing down from the positions shown in dotted lines in Fig. 5 to the positions shown in full lines where they enter the openings 318 in the guide plates 316, and press against 85 the end flaps of the package so as to apply adhesive (or other liquid) thereto, dwelling a brief instant in contact therewith and then swinging back to their dotted line positions. These swinging movements are imparted by a cam 336 fixed on shaft 34 acting 90 through lever 337 (Fig. 3) which connects by link 338 to a vertically moving slide 339 (Fig. 4) sliding in a fixed frame 340 and having on its opposite sides upright racks 95 341 which mesh with pinions or sectors 342 (Figs. 4 and 5), which pinions are fast on the ends of the shafts M' . Thus the cam action drives the slide 339 up and down, and its racks impart the necessary rotation of 100 about 90 degrees at each movement of the rock shafts.

The mechanism for applying the labels to the ends of the package is best shown in 105 Figs. 4 and 6, and the driving means therefor in Figs. 3 and 4. The operation of this mechanism has already been explained. Each of the slides Q , which carry the carriers Q' for the magazines P , is reciprocated by movement taken from a cam 350 on the lower shaft 32, the cam roller being carried 110 on a lever 351 having a slot and pin connection with another lever 351', which levers transmit movement to the respective slides through links 352, elbow levers 353 and 115 links 354, Fig. 3. For turning little by little the screw P^2 for propelling forward the follower P' , the square shaft P^4 attached thereto passes with a sliding connection 120 through a square hole in the hub of a worm wheel P^3 which is turned by a worm 360 (Fig. 4) on the shaft 362 on which is a pulley 361 driven by a belt 363 from any convenient source, as, for example, a pulley 364 on one of the cam shafts 28 and 34 125 (see Fig. 2).

130 After the labels are affixed the next feeding movement carries the package with its end labels beyond the holes 318 and into engagement with the continuous portions

of the guide plates 316 which hold the labels pressed against the end flaps, as well as holding the latter pressed against the package. The packages are finally pushed out 5 endwise by an ejecting pusher (not shown) along a trough U wherein their ends are pressed together, thereby prolonging the time during which the end flaps and labels are held in close contact.

10 The mechanism thus described accomplishes the operation of labeling the ends of the packages or other articles very effectively, and is quite automatic, except for the attention required in re-filling the magazines with labels, when the last of the latter 15 are fed out. At this time it is necessary to screw back the feeding screw P² to bring the follower to its initial position.

While the machine has been described 20 with great precision with respect to the particular embodiment of the invention illustrated it is to be understood that the invention may be varied to a considerable extent 25 in mechanical respects, within the scope of the appended claims.

We claim as our invention:

1. Mechanism for applying adhering labels to an article, comprising a magazine carrying a stack of labels, a follower for 30 pressing against the stack of labels, a reciprocating carrier on which said magazine and follower are mounted, a slow-feed advancing means adapted to move said follower with respect to the said magazine 35 to compensate for the diminution of the label stack, and a yielding means interposed between the label stack and said reciprocating carrier, whereby the labels may be pressed yieldingly against the article and 40 without subjecting it to the impact of the reciprocating carrier.

2. Mechanism for applying adhering labels to an article, comprising a magazine for carrying a stack of labels, a follower for 45 pressing against the stack of labels, a reciprocating carrier therefor having a fixed stroke and adapted to move said follower toward and from an article to be labeled, a yielding slow-feed follower-advancing means 50 adapted to yieldingly move said follower relatively to said carrier to compensate for the diminution of the label stack and means independent of the label stack for advancing the said magazine toward the article to 55 be labeled.

3. Mechanism for applying adhering labels to an article, comprising a magazine having a restricted delivery end and containing a stack of labels, a follower for 60 pressing against said stack of labels, a reciprocating carrier on which said magazine and follower are mounted, a slow-feed follower-advancing means adapted to move said follower relatively to said carrier, and yielding means between said magazine and

said carrier, said yielding means tending to move the restricted delivery end of the magazine away from the said label follower whereby the edges of the labels are relieved from pressure tending to bind them against 70 the said restricted delivery end of the magazine.

4. The combination of claim 3, further characterized in that a yielding connection is interposed between said follower and said 75 carrier.

5. Mechanism for applying adhering labels to an article, comprising a magazine containing a stack of labels, a follower within the magazine, a reciprocating carrier for such magazine and follower, and slow-feed means reciprocating with the carrier and adapted to be continuously rotated from a non-reciprocating part of the mechanism. 85

6. Mechanism for applying adhering labels to an article, comprising a magazine containing a stack of labels, a follower within the magazine, a reciprocating carrier for such magazine and follower, and slow-feed means to compensate for the diminution of the label stack, said means comprising two screwthreaded elements having mutually-engaging threads, both of said elements partaking of the reciprocating motion of said 90 carrier and one of them slidably engaging a rotating means carried by a fixed part of the mechanism, whereby a continuous rotary movement is transmitted from a non-reciprocating part of the mechanism to a 100 reciprocating part of the slow-feed means.

7. Mechanism for applying adhering labels to an article, comprising a magazine containing a stack of labels, a follower within the magazine, a reciprocating carrier 105 for such magazine and follower, and slow-feed means for advancing the follower with respect to the magazine to compensate for the diminution of the label stack, said means comprising two cooperating screwthreaded 110 elements having mutually-engaging threads, said cooperating elements being interposed between said reciprocating carrier and the label follower, and rotating means to effect independently of the reciprocation of such carrier a relative rotation between said 115 threaded elements.

8. The combination of claim 6, further characterized in that said rotating means comprises a worm-driven wheel slidably 120 splined on one of said screwthreaded elements and held against axial displacement by a member attached to a fixed part of the mechanism, whereby the rotation of said wheel may be continuously imparted to said 125 element regardless of the longitudinal displacement thereof.

9. Mechanism for applying adhering labels to an article comprising a magazine having a restricted delivery end and con- 130

taining a stack of labels, a follower for pressing against the stack of labels, and a reciprocating carrier on which said magazine and follower are mounted, a slow-feed 5 advancing means to compensate for the diminution of the label stack, and means adapted to momentarily continue the engagement of said magazine with the article to be labeled while said follower is being withdrawn, whereby the pressure on the label stack acting against the restricted delivery end of said magazine is reduced to facilitate the withdrawal of a label.

10. Mechanism for applying adhering labels to an article, comprising a magazine having a restricted delivery end and containing a stack of labels, a follower for

pressing against said stack of labels, a reciprocating carrier on which said magazine and follower are mounted, a slow-feed 20 follower-advancing means adapted to move said follower relatively to said carrier, a yielding connection between said follower-advancing means and said magazine, and another yielding connection between said carrier and said follower-advancing means, both of said yielding connections being adapted to exert a force tending to move the magazine toward the article to be labeled.

25 In witness whereof, we have hereunto signed our names.

PAUL H. GRIMM.
FRANK L. COCKS.
